(57) **CLAIM**

The ornamental design for a wound therapy device, as shown and described.

DESCRIPTION

FIG. 1 is a front perspective view of a wound therapy device of our design;

FIG. 2 is a rear perspective view thereof;

FIG. 3 is a front view thereof;

FIG. 4 is a rear view thereof;

FIG. 5 is a right side view thereof;

FIG. 6 is a left side view thereof;

FIG. 7 is a top view thereof; and

FIG. 8 is a bottom view thereof.

FIG. 9 is a front perspective view of a second embodiment of a wound therapy device;

FIG. 10 is a rear perspective view of the second embodiment;

FIG. 11 is a front view of the second embodiment;

FIG. 12 is a rear view of the second embodiment;

FIG. 13 is a right side view of the second embodiment;

FIG. 14 is a left side view of the second embodiment;

FIG. 15 is a top view of the second embodiment; and,

FIG. 16 is a bottom view of the second embodiment.

The stippled shading in certain portions of FIGS. 9-16 indicates color contrast. Features shown in dotted lines are for illustrative purposes only and form no part of the claimed design.
